US00D706084S

(12) **United States Design Patent**
Manley

(10) **Patent No.:** **US D706,084 S**
(45) **Date of Patent:** **** Jun. 3, 2014**

(54) **LIDDED CONTAINER**

(71) Applicant: **Sistema Plastics Limited**, Auckland (NZ)

(72) Inventor: **James Richard Manley**, Auckland (NZ)

(73) Assignee: **Sistema Plastics Limited**, Auckland (NZ)

(**) Term: **14 Years**

(21) Appl. No.: **29/438,302**

(22) Filed: **Nov. 28, 2012**

(30) **Foreign Application Priority Data**

Jun. 19, 2012 (NZ) 416414
(51) **LOC (10) Cl.** **07-01**

(57) **CLAIM**

The ornamental design for a lidded container, as shown and described.

DESCRIPTION

FIG. 1 is a top, front perspective view of a lidded container showing my new Design;

FIG. 2 is a top plan view thereof;

FIG. 3 is a front elevational view thereof;

FIG. 4 is a rear elevational view thereof;

FIG. 5 is a left side elevational view thereof; and,

FIG. 6 is a right side elevational view thereof.

The broken lines in FIGS. 1, 3-6 of the lidded container are for the purpose of illustrating environment, and form no part of the claimed design.

1 Claim, 6 Drawing Sheets
